UNITED STATES PATENT OFFICE.

WILLIAM EDGE, OF NEWARK, AND ALLAN H. JONES, OF EAST ORANGE, NEW JERSEY.

CAN-OPENER.

1,135,571.

Specification of Letters Patent. Patented Apr. 13, 1915.

Application filed June 9, 1914. Serial No. 843,953.

To all whom it may concern:

Be it known that we, WILLIAM EDGE and ALLAN HETRICK JONES, citizens of the United States, and residents of Newark, Essex county, New Jersey, and East Orange, Essex county, New Jersey, respectively, have invented certain new and useful Improvements in Can-Openers, of which the following is a specification.

10 The object of this invention is to provide a simple and efficient device capable of cutting the tops off of tin cans, and the like, with facility.

The invention comprises novel details of 15 improvement and combinations of parts that will be more fully hereinafter set forth and then pointed out in the claims.

Reference is to be had to the accompanying drawings forming part hereof, wherein, 20 Figure 1 is a side elevation of a can opener embodying this invention; Fig. 2 is a plan view thereof; Fig. 3 is an enlarged detail section of the upper portion of the device; Fig. 4 is a similar view of the lower portion of the device, and Fig. 5 is a detail section substantially on the line 5, 5, in Fig. 2.

Similar numerals of reference indicate corresponding parts in the several views.

At one is indicated a suitable frame, having an upper laterally disposed arm 1^a, and 30 centrally beneath said arm the frame 1 is provided with a guide or bore 2. Frame 1 is adapted to be secured against a wall or other support, as by means of screws passing 35 through suitable holes in the frame.

At 3 is a rotative disk having depending 40 projections or pins 4 suitably spaced apart, adapted to enter the top of a can 5 for rotating the latter. Disk 3 is shown carried by a hub 6 provided with a bevel gear 7 meshing with a pinion 8 on shaft 9, having a crank 9^a, suitably journaled in a bearing 10 on arm 1^a, whereby when said shaft is rotated the projections or pins 4 will be correspondingly rotated.

At 10 is a support or shelf for the can 5, 45 rotatively supported upon the upper end of a rod 11 shown provided with a rack 12, and guided in a bearing or bore 2, the axis 50 of rod 11 and of support or shelf 10 being in vertical alinement with the axis of a gear 7 and projections or pins 4.

A shaft 13 is journaled on the lower arm 55 of frame 1 and carries a gear 14 meshing with rack 12, said shaft being provided with

a crank 15, whereby when said shaft is rotated the rod 11 may be raised and lowered.

At 16 is a stop dog adapted to engage gear 14 to prevent rod 11 from dropping under the weight of the can, said dog being shown 60 carried by arm 17 that is pivoted at 18 upon the frame.

At 20 is an arm or lever pivotally supported, as at 21, upon arm 1^a, in such position as to be swung toward and from can 5. 65 By preference, a spring 22 bears against arm 1^a and arm or lever 20 to normally retain the latter away from the can. Arm or lever 20 carries a cutter 23, preferably two-edged, and pointed, as shown, to be readily pressed 70 into the side of the can. Arm 20 also carries an abutment 24 immediately above knife 23. Said cutter and abutment are shown seated in a recess 20^a in the top of arm 20, and in the example illustrated a screw 25, 75 passing through holes in knife 23 and abutment 24 and meshing in threads in arm 20, secures said knife and abutment firmly to said arm.

When the can opener is to be used, the rod 11 and support 10 are sufficiently lowered to enable the can to be centered on support 10, and then crank 15 is rotated to cause the parts 10, 11 and the can to be raised, 80 whereby the can top is pushed against projections or pins 4 to cause the latter to pierce and enter the can top. Arm or lever 20 may then be swung toward the can, and pushed so that the cutter 23 enters the side of the can, and the abutment 24 bears 85 against the can to control the position of the knife in the can, the arm and knife being suitably held by the hand, and then crank 9^a is rotated, whereby with the gear and projections or pins 4 the can is rotated 95 against the cutter which causes the upper portion of the can to be cut, as upon the line 5^a, in Fig. 1. By this means the top portion of the can may be cut away and lifted or swung from the can. The arrangement provides for cutting the tops off of cans of varying heights and widths, and the position and operation of the arm or lever 20 enables the cutting off of the tops of cans that are round as well as other shapes, 100 such as rectangular, since the arm or lever 20 may be caused to follow the contour of the can, the abutment 24 being held with proper pressure against the side of the can.

After the can top has been cut, as described, 110

the parts 10, 11 and the can may be lowered by first lifting the dog 16 from gear 14.

The improvements described are simple and relatively cheap to manufacture, may be readily operated, and avoid danger of the operator being cut by the can when its top is being severed.

Having now described our invention what we claim is:—

- 10 1. A can opener comprising a frame, a can support, means upon the frame for raising and lowering said support and holding it in set position, a gear rotatively carried by the frame above said support, projections depending from the gear to enter a can top, means to rotate said gear, an arm carried by the frame at one side of the projections adapted to move toward and from the side of the can, and a cutter carried by said 15 arm adapted to enter the side of the can.
- 20 2. A can opener comprising a frame, a can support, means upon the frame for raising and lowering said support and holding it in set position, a gear rotatively carried by the frame above said support, projections depending from the gear to enter a can 25 top, means to rotate said gear, an arm carried by the frame at one side of the projections adapted to move toward and from the side 30 of the can, and a cutter carried by said arm adapted to enter the side of the can, said arm having an abutment adjacent to said cutter to engage the side of the can to regulate the entry of the cutter into the can.
- 35 3. A can opener comprising a frame, a can support, means upon the frame for raising and lowering said support and holding it in set position, a gear rotatively carried by the frame above said support, projections 40 depending from the gear to enter a can top, means to rotate said gear, an arm carried by the frame at one side of the projections adapted to move toward and from the side 45 of a can, a cutter seated upon and extending transversely of the arm toward the can, an abutment located against and above the cutter to engage the can side, the cutter extending farther from the arm than the abutment and means securing said cutter 50 and abutment together upon said arm.
- 55 4. A can opener comprising a frame, a can support, means upon the frame for raising and lowering said support and holding it in set position, a gear rotatively carried

by the frame above said support, projections depending from the gear to enter a can top, means to rotate said gear, an arm carried by the frame at one side of the projections adapted to move toward and from the side of a can, said arm having a recess, a 60 cutter and an abutment in said recess, the abutment extending toward the can beyond the arm, and the cutter extending beyond the abutment toward the can, and means securing the cutter and abutment in said 65 recess.

5. A can opener comprising a frame having an upper laterally disposed arm, a gear journaled upon said arm, projections depending from the gear to enter a can top, 70 means upon the arm to rotate said gear, a horizontal arm pivotally supported from the first named arm to swing laterally relatively to the can, a cutter carried by the second named arm and projecting laterally 75 therefrom toward the can, said frame having a bearing axially disposed beneath the cutter, a rod guided in said bearing, a can support swivelled upon said rod, and means to retain said rod in set positions of elevation.

6. A can opener comprising a frame having an upper laterally disposed arm, a gear journaled upon said arm, projections depending from the gear to enter a can top, 85 means upon the arm to rotate said gear, a horizontal arm pivotally supported from the first named arm to swing laterally relatively to the can, a cutter carried by the second named arm and projecting laterally 90 therefrom toward the can, said frame having a bearing axially disposed beneath the cutter, a rod guided in said bearing and provided with a rack, a pinion journaled upon said frame and engaging said rack, a 95 crank to rotate said gear, a dog to engage said gear to retain the rod and can support in set positions of elevation, and means movably supporting said dog upon said frame.

Signed at Newark in the county of Essex 100 and State of New Jersey this sixteenth day of May A. D. 1914.
